UNITED STATES PATENT OFFICE

ELMER R. POPE, OF HAMILTON, MASSACHUSETTS, ASSIGNOR TO UNITED SHOE MACHINERY CORPORATION, OF PATERSON, NEW JERSEY, A CORPORATION OF NEW JERSEY

MACHINE FOR OPERATING UPON THE HEEL-PORTIONS OF SHOES

Application filed April 26, 1928. Serial No. 272,953.

My invention relates to machines for operating upon the heel-portions of shoes, it being herein disclosed as embodied in an apparatus for inserting fastenings, which may 5 be those by which heels are attached.

An object of the invention is to provide a fastening-inserting machine having an improved work-support or jack adapted for such operations as inserting fastenings from 10 within a jacked shoe to secure the heel from the inside. To this end, I provide novel means for driving in each heel a fastening in a direction inclined to the longitudinal axis of the jack and from the rear toward the toe- 15 portion of the shoe, and for varying simultaneously the extension of plural drivers from their carrier. The inclined fastenings may be placed at the rear of heels having a heavy pitch, as those of the Louis type, their inclina- 20 tion permitting them to be located close to the edge, and giving a tight crease, where a fastening driven straight would be less effective because of its necessary spacing from the periphery. The gang-adjustment of the 25 drivers, other than the one inclined at the rear of the heel, gives a ready means for altering the relation of the ends of the drivers to the work-supporting surface of the jack, so that a multiple driver-assembly correspond- 30 ing to a plurality of nailing designs may be used selectively. The drivers for the designs not employed are prevented from indenting and mutilating the insoles of the shoes being heeled.

35 This invention has as a further object the provision of an effective pressure-head or abutment, which will hold the work in place upon the jack for heel-attachment or other operations upon it. To this end, I include a 40 member which is brought into engagement with each heel, as at the breast, by movement about a pivotal mounting after contact between the abutment and heel has been established through an opposite member or members, as 45 those engaging the rear of the heel. The breast-contact member may thus be held normally clear of the jack to leave it free at the front to receive the work, and then, when the heel is in place, carried against the forward 50 curved portion of the breast, where it merges

into the shank. Here it retains the heel securely against forward displacement along the shoe-bottom and also against separation from the heel-seat. This arrangement is of particular utility when combined with means 55 for driving heel-attaching nails in a forwardly inclined direction. To insure that one of the contact members, as that at the heel-breast will not yield under the pressure applied, I have provided the illustrated construction with a locking member for the contact member, with which is associated means for releasing it at the desired time. Adjustments are preferably furnished for 60 positioning both the breast-contact member 65 and the opposite member or members which engage the rear of the heel. By these adjustments, the most effective retaining action upon a heel is obtained. Reference has been made to furnishing a free space to apply the 70 work to the jack or other support. In my improved pressure device, the illustrated rear contact member is movable upon said device for thus approaching and retreating from the jack, and this movement I cause by means, as 75 a lever actuated in the travel of the pressure device itself, along which the contact member moves. This organization effects, in a simple manner, a jack-freeing movement of sub- 80 stantial extent.

In the accompanying drawings illustrating a particular embodiment of the invention,

Fig. 1 shows, partly in broken side elevation and partly in vertical section, a jack and pressure-head of a heel-attaching machine, to which my improvements are applied, the parts being in their normal position;

Fig. 2 is a similar view, with the elements 90 in operating position;

Fig. 3 is a detail in broken perspective of the upper portion of the jack;

Fig. 4, a horizontal section on the line IV—IV of Fig. 1;

Fig. 5, an enlarged vertical sectional detail on the line V—V of Fig. 4;

Fig. 6, a broken front elevation of the parts appearing in Figs. 1 and 2;

Fig. 7, an enlarged vertical sectional de- 100

tail in the plane of the rear driver-passage; and

Fig. 8, a transverse section through the rear driver-passage of the jack-top.

5 The general structure of the machine may resemble that of Letters Patent of the United States No. 1,269,654, Standish, June 18, 1918, which is particularly designed for the attachment of heels to shoes by nails driven through 10 the soles from the inside. This includes a frame F, upon which is mounted a work-supporting jack J with its longitudinal axis arranged in a fixed vertical relation, and a head P, which reciprocates upon the frame 15 from an elevated position (Fig. 1), leaving the jack free for the application of the work, to one (Fig. 2) in which it applies pressure to clamp a heel H in attaching relation upon the heel-seat of a jacked shoe S.

20 The jack includes a base 10, preferably of cast metal, the front of which is flattened at 12 and is provided with a horizontal groove or depression to receive a projection 16 upon a bar 18 rising vertically from the base. The 25 upper extremity of the bar is divided to receive the portion 20 of a jack-top 22 secured in place between the spaced walls of the bar and extending rearwardly over the base. A curved shield 24, which is preferably of sheet-metal, may enclose the space between the base and top, in which space the nail-driving assembly operates under the power of the machine. This shield is shown as attached to the opposite sides of the bar. A jack-post 30 thus constructed is comparatively light in weight, yet amply strong, and the absence of the customary cast wall at the rear so reduces the size of the post in this direction that a greater space is afforded to receive the forwardly extending rear portions of uppers of 35 some types of shoes. A jack having an integral cast post may, if it has the necessary strength, be so thick at its rear wall as to interfere with the proper application of the 40 work.

45 The driver-assembly includes a plunger or carrier 26 guided for vertical reciprocation in the base 10 and having mounted on its upper portion drivers 28, which operate in 50 openings 30 in the jack-top. The present assembly includes in multiple the drivers for a plurality of nailing designs, there being shown in the drawings three groups corresponding to three distinct designs. The 55 openings 30 are correspondingly arranged, the nails being supplied only to the openings of the design which is in use. If all the drivers were allowed to rise to the full nail-inserting extent, at which the heads of the 60 attaching nails are sunk in the insole, those belonging to the designs not at the time employed would also be forced into the insole, unnecessarily defacing it. This I avoid by varying the extension of the drivers above 65 their carrier and into the openings in the

jack-top. To facilitate the change, the adjustment is effected simultaneously in sets of drivers. Herein, four of these sets *a*, *b*, *c* and *d* are illustrated, each set including one driver of each of the three designs. In 70 each set, the order of the drivers belonging to different designs is the same, that for the smallest nailing being at the right in Fig. 4, with the largest at the left. Each driver is arranged to move vertically through an opening in a plate 32 (Fig. 5) secured to the top of the carrier 26, there being an enlargement 34 upon each driver beneath the plate. Between this enlargement and the under surface of the plate, about each driver, is a spring 36, the effect of which is to hold the lower end of the enlargement 34 against an eccentric portion 38 upon a spindle 40 mounted horizontally for rotation in a bore in the carrier. There is a spindle having three eccentric portions for each of the driver-sets *a*, *b*, *c* and *d*. When an eccentric support is in 75 its uppermost position, as is that at the right of Fig. 5, the corresponding driver will be so elevated that its upper extremity will rise 80 slightly above the work-supporting surface of the jack-top when the nail it carries is inserted. The other eccentricities of the same spindle have such an angular relation that they hold their drivers so these are maintained within the openings 30 and do not contact with the insole of the shoe being operated upon. This allows the angular adjustment of the spindles to determine the driver which shall be effective, and therefore the 85 design which shall be nailed. The angular relation of each spindle may be altered by turning it by a tool engaging a slot 42 at the open extremity of the bore, and access may be had to these through openings in the shield 24 covered by pivoted closures 44 (Fig. 4). To determine and fix the position of each spindle, it has a circumferential series of depressions 46, any one of which may be entered by a 90 spring-actuated plunger 48 movable in the carrier at one end of a set of drivers. Rotating the spindles until the corresponding depressions 46 in all are engaged by their plungers arranges the entire multiple-assembly for the nailing of a chosen design, at 95 the same time rendering the drivers of other designs incapable of contacting with the insole.

100 When a heel has a forward inclination resembling that illustrated in the drawings, it is obviously impossible to insert a rear nail perpendicular to the general plane of the heel-seat and close to the periphery. It would emerge through the outer wall. On the other hand, failure to keep near the edge tends to produce a gaping crease. A desirable arrangement is to have the rear nail follow the general inclination of this portion of the heel, but the mechanism necessary to accomplish this is difficult to mount in the limited space 105 110 115 120 125 130

available in the jack-top; and drivers applied to such purposes are frequently subjected to strains which quickly break them. I avoid these difficulties in the following manner: At 5 the rear of the jack-top is a downwardly inclined portion 50, most clearly illustrated in Fig. 3 of the drawings, which may depend from a piece 52 inserted at the center of the top. The inclination of the portion 50 is substantially that at which it is desired to drive the rear nail. In the upper face of the inclined wall is a groove 54, with which registers an opposite groove 56 in a cover-piece 58 attached to the piece 52. In the cover piece is 10 an opening 60 alined with the opposite grooves 54 and 56 and furnishing with them a nail- and driver-passage which is rectilinear throughout its length. Movable in the passage is a short, rigid driver 62, from the opposite sides of which are projections 64, 64 operating through extended spaces 66, 66 between the inclined portion 50 and the cover-piece 58. Cylindrical ends 67 of the projections are engaged by the separated forked extremities of an actuating lever 68 fulcrumed in a space at the rear of the jack-top, and held normally down with the driver retracted by a spring 70, the driver being offset outwardly from the lever-fulcrum. Mounted to 15 move vertically in the jack-top is a slide 72 joined by a link 74 to the lever. Situated at the top of the driver-carrier 26 is an adjustable contact member furnished by a screw 76 (Figs. 1 and 2). When the carrier rises to 20 produce the nail-inserting movement of the drivers 28, the contact-screw 76, near the end of the driver-movement, strikes against the slide 72, quickly raising this and, through the link 74 and lever 68, forcing the driver 62 through its passage to drive the rear nail. This may be made to follow closely the inclination of the rear of the heel H, and therefore may be placed close to the crease, holding this firmly closed. It will be seen that the 25 driver 62 is so short that, in spite of its inclination, it lies wholly within the counter-portion of a jacked shoe, in no way interfering with the support of the latter, and that this limited extension prevents the drivers from being broken readily. There is also a freedom from weakening lateral strains which might result were a curved path followed. Its operating mechanism is simple and positive in action and may be mounted in 30 a very limited space.

The pressure-head P has horizontal ways 80, in which is adjustable, by a screw and hand-nut 82, a carrier 84. This adjustment permits contact members mounted upon the carrier to be correspondingly positioned longitudinally of the shoe to be heeled. Movable vertically in the carrier is a slide 86, in the lower extremity of which are horizontal ways 88 lying transversely of the jacked shoe. In 35 these ways, a primary horizontal slide 90 may

be adjusted by opposite screws 92 threaded into the vertical slide 86 with their heads bearing against the opposite sides of the slide 90. By these screws, the position of the horizontal slide may be varied and fixed to produce the correct transverse relation of the supported contact members. Extending in the slide 90 longitudinally of the jacked shoe are ways 94, and movable in these ways is a secondary slide 96, at opposite sides of which are depending arms 98. Pivoted near the bottom of each arm is a bell-crank lever 100 (Figs. 2 and 6). Each lever has a substantially horizontal arm and a depending arm, and from the latter is a forwardly extending projection 102, upon which is held, for angular adjustment, a member 108 arranged for contact with one side of the heel H near the rear and close to the crease. Through a portion 104 of the lever 100 are threaded screws 106, which, pressing at their inner ends against the outer face of the member 108, fix it normally against turning about the projection 102. The adjustment of the member 108 permits its inclination to be altered to best suit the form of the heel operated upon. A rounded end 110 of the horizontal arm of each lever 100 enters a depression at one side of a slide 112 guided for vertical movement in a recess in the secondary slide 96. 40 A spring 114, located in a bore at the top of the slide 112, urges toward the rear of the heel, between the members 108, 108, a contact member 116 joined to the slide 112 by a universal connection 117. This mounting permits the member 116 to adapt itself to the inclination of the heel operated upon. When the pressure-head is lowered in its clamping movement, the center member 116, forced down by its spring, holds the side members 108, 108 raised. But when contact between the center member and the heel is established, the spring 114 yields, and the consequent elevation of the member 116 causes the levers 100 to be turned upon their pivots to bring the members 108 against the opposite sides of the heel, which is thus held at the rear against both upward and lateral displacement. The entire rear contact device is held normally at its lowest extreme of movement upon the carrier 84 by a spring 118 (Fig. 1) seated in a vertical bore in the slide 86 and bearing at its upper extremity against a plate secured to the carrier. This spring is more resistive to compression than the spring 114, to permit the closing of the side contact members 108 upon the heel before the rise of the rear contact device as a whole. A spring 120 connecting the slide 96 with the frame holds said slide with its contact members normally in their extreme rearward position. Thus, when the head P is raised, the rear contact members are held spaced from the jack both vertically and horizontally to give ample space to apply the work. 45

To bring the members 108, 108 and 116 forward over the rear of the heel for engagement with this in the descent of the head, this vertical travel of the head is caused to move the slide 96 in the ways 94. Fulcrumed upon the frame F above the head P is a lever 122, the lower end of which is so located that a roll 124 at the rear of the slide 96 is held against it by the spring 120. A roll 126 upon the lever 10 lies just at the lower extremity of a cam-incline 128 carried by the head P, this relation existing when the head is at its upper limit of movement. As the head descends to clamp the heel in its attaching position, a vertical 15 surface 130 follows the incline 128 in contact with the roll 124. The effect of this is to first cam the lever 122 quickly against the roll 124, and thus force the slide 96 forward so that its contact members 108, 108 and 116 20 are directly above the points on the heel which they are to engage. Then the surface 130 locks the lever against reverse movement, and holds the slide 96 with its members in position for the application of pressure. This 25 organization, without a cam-surface 128 of very abrupt inclination, may be caused to produce a rapid forward movement of the slide 96 through a considerable distance on account of the multiplying effect of the lever 30 122. To allow the surfaces 128 and 130 to be most advantageously located with respect to the roll 126, they may be formed upon a block 131 attached to the head by slot-and-screw 35 connections 133. The block with its actuating surfaces may thus be vertically adjusted and fixed at the chosen point.

Fulcrumed upon the carrier 84, in front of the slide 86, is a lever 132 carrying a heel-breast-contact member 134. Upon an arm of the lever, at the rear of the fulcrum, is a gear-segment 136 (Fig. 1), with which meshes a rack 138 formed upon the forward edge of the slide 86. When the rear contact members are held lowered by the spring 118, these 40 gearing connections swing the breast-contact member to its maximum height to give the necessary space to apply the work to the jack. After engagement of the rear contact members 108, 108 with the heel, the slide 86 is 45 held stationary, compressing the spring 118 in the descent of the head; whereupon the gearing 136, 138 turns the lever 132 to carry the contact-portion 134 downwardly and rearwardly against the curved portion h of the heel-breast. This engagement very effectively resists forward displacement of the heel along the shoe-bottom, as well as separation of the heel outwardly at the breast from the heel-seat. The former movement is 50 especially likely to occur when, as in the present instance, attaching nails are driven inclined from the rear toward the breast of the heel.

To cause the contact member 134 to approach and engage the portion h of the heel-

breast at the most effective angle, the forward arm of the lever is made in two sections, pivoted together at 140 and joined by a worm 142 rotatable in one section, and a worm-wheel segment 144 formed upon the other. When the worm is rotated by a finger-piece 146 at its upper end, the contact member 134 may be moved in or out, as desired, to give the best angle of approach.

It will be seen that, as in the apparatus of the previously mentioned patent, after contact has been established between the heel which is held, for angular adjustment, a members, there should be a balance of forces holding these members against relative movement through their action upon their connecting gearing 136, 138. Because of the leverage of the arm 132 through which the reaction of the member 134 is transmitted, this may so overcome the force of the rear members as to tend to lessen the resistance to forward displacement of the heel. Therefore, I prefer to lock the breast-contact member against reverse movement during the application of pressure. For this purpose, there swings with the lever 132 a ratchet-segment 148, with the teeth of which co-operates a detent 150 pivoted upon the carrier 84 and acting under the influence of a spring 152. As the member 134 descends, the engagement of the detent with the ratchet-teeth furnishes a lock effective throughout its advance, and the resistance to forward displacement of the heel is made positive. Upon the elevation of the pressure-head P at the completion of the attaching operation, the tail of the detent strikes a contact member 154 adjustably fixed upon the frame by slot-and-screw connections 155. This raises the engaging point of the detent 45 from the ratchet-teeth, releasing the lever 132 for the succeeding operation.

The general action of the machine is as follows: If necessary because of a change in the size and form of the heel, the drivers are adjusted by rotation of the spindles 40 to make fully effective only those of the desired nailing design, and correct relation of the contact members to the jack is established by adjustment of the members 82, 92 and 146. These last three respectively position all the contact members longitudinally of the shoe which is to be operated upon, the rear member transversely thereof, and the breast member angularly. Nails are inserted in the openings 30 of the design in use and in the rear opening 60, the shoe S to be heeled is jacked, and its heel H placed upon the heel-seat. Then, upon starting the machine in operation, the head P is caused to descend, the cam-incline 128 forcing forward the actuating lever 122 and thus carrying the slide 96 with the rear contact members over the heel. Continued downward travel of the head brings the center rear member 116 against the heel, and this, remaining stationary and 50

compressing the spring 114 as the descent of the head continues, closes the side members 108, 108. Downward travel of all the rear members being thus checked by the heel, the 5 spring 118 is compressed by the slide 86, and, through the gearing 136, 138, the lever 132 is turned to bring the contact member 134 from its raised position against the curved wall λ , where the breast of the heel merges into the 10 shoe-bottom. Some further downward movement of the head forces both the rear and breast members against the heel to clamp it in place, yield of the latter member being prevented by the lock furnished by the detent 150 in engagement with the ratchet 148. Lateral displacement of the heel upon the heel-seat is effectively prevented in all directions by the four encircling members. Elevation of the driver-carrier 26 now begins, 20 and the nails upon the drivers 28 of the selected design are forced through the shoe-bottom into the heel. Before the completion of this inserting movement, the contact-screw 76 strikes the slide 72, and the inclined driver 25 62 is caused to insert the rear nail. The attachment of the heel having thus been completed, the driver-carrier descends, and the head P rises, freeing the heel from the contact members, which are restored by the 30 springs 118 and 114 to their normal positions upon the carrier. The ascent of the head releases the lever 122 from the cam-surfaces 130 and 128, allowing the slide 96 with the rear contact members to be returned by the 35 spring 120 to the normal position clear of the jack. The apparatus is now ready for the next operation.

Having described my invention, what I 40 claim as new and desire to secure by Letters Patent of the United States is:

1. In a fastening-inserting machine, a work-support having a rectilinear fastening-receiving passage inclined with respect to the longitudinal axis of said support, a rigid driver movable in the passage, a driver-actuator supported upon the jack, the driver being offset outwardly from the actuator-support, and means for moving the actuator to reciprocate the driver.

2. In a heel-attaching machine, a jack having a nail-receiving passage, a driver movable in the passage, a lever fulcrumed about a fixed point upon the jack and connected to the driver, and means connected to the lever for actuating the driver.

3. In a heel-attaching machine, a jack having a nail-receiving passage, a driver movable in the passage, a member movable upon the jack, pivotal connections between the 60 member and driver, a slide mounted upon the jack, connections between the slide and member, and means for moving the slide.

4. In a heel-attaching machine, a jack having a nail-receiving passage, a driver movable in the passage, a lever fulcrumed upon

the jack and connected to the driver, a slide reciprocating in the jack, a link pivoted to the slide and driver, and a driver-plunger arranged to actuate the slide.

5. In a fastening-inserting machine, a work-support having a rectilinear fastening-receiving passage inclined with respect to the longitudinal axis of said support, a driver movable in the passage, a lever fulcrumed about a fixed point upon the support adjacent to the passage and connected to the driver, and a driver-plunger movable in the support and arranged to actuate the lever.

6. In a fastening-inserting machine, a reciprocatory carrier, means for reciprocating the carrier, drivers movably mounted upon the carrier, and means arranged to vary simultaneously the extension of a plurality of drivers from the carrier.

7. In a fastening-inserting machine, a reciprocatory carrier, drivers movably mounted upon the carrier, and means arranged to vary simultaneously to different degrees the extension of a plurality of drivers from the carrier.

8. In a fastening-inserting machine, a reciprocatory carrier, drivers movably mounted upon the carrier, and a member movable upon the carrier and having differently arranged portions respectively co-operating with different drivers.

9. In a fastening-inserting machine, a reciprocatory carrier, drivers movably mounted upon the carrier, and a rotatable member having a plurality of eccentric portions respectively co-operating with different drivers.

10. In a fastening-inserting machine, a reciprocatory carrier, drivers movably mounted upon the carrier, a member movable upon the carrier and having differently arranged portions respectively co-operating with different drivers, and means arranged to fix the member in a plurality of predetermined positions.

11. In a fastening-inserting machine, a reciprocatory carrier, drivers movably mounted upon the carrier, a rotatable member having a plurality of eccentric portions respectively co-operating with different drivers, and a latch constructed and arranged to fix the member in different angular positions.

12. In a fastening-inserting machine, a reciprocatory carrier, a driver movably mounted upon the carrier, a spindle rotatable upon the carrier and provided with an eccentric portion, and a spring arranged to force the driver into contact with the eccentric.

13. In a fastening-inserting machine, a reciprocatory carrier, drivers movably mounted upon the carrier, and a spindle rotatable upon the carrier and provided with a series of eccentric portions having differ-

ent angular relations and arranged for engagement with the drivers.

14. In a fastening-inserting machine, a reciprocating carrier, drivers movably mounted upon the carrier, a spindle rotatable upon the carrier and provided with a series of eccentric portions having different angular relations and arranged for engagement with the drivers, there being a circular series of 10 depressions about the spindle corresponding in number to the eccentric portions, and a plunger mounted in the carrier and arranged to enter the depressions.

15. In a nailing machine, a multiple driver-assembly arranged to insert nails in accordance with a plurality of nailing designs, and means acting upon drivers belonging to different designs and arranged to selectively render fully effective the drivers of any one 20 of the designs.

16. In a heel-attaching machine, a jack provided with driver-passages corresponding to a plurality of nailing designs, multiple drivers reciprocating in the passages, and 25 means acting simultaneously upon the drivers of a plurality of designs and arranged to maintain all but those belonging to a particular design below the work-supporting surface of the jack.

30 17. In a heel-attaching machine, a jack provided with driver-passages corresponding to a plurality of nailing designs, a reciprocating carrier, drivers movable upon the carrier and extending into the passages, and driver-moving members mounted upon the carrier, each member having portions contacting with the drivers of all the designs.

40 18. In a heel-attaching machine, a jack provided with driver-passages corresponding to a plurality of nailing designs, a reciprocating carrier, drivers movable upon the carrier and extending into the passages, and a series of eccentrics rotatable together upon the carrier and contacting with drivers of all 45 the nailing designs.

50 19. In a shoe-nailing machine, a jack-post comprising a cast-metal base, a bar rising from the front only of the base and secured against movement thereon, and a jack-top 55 fixed to the bar and extending rearwardly over the base.

20. In a shoe-nailing machine, a jack-post comprising a cast-metal base, a bar rising from the front only of the base and secured 55 against movement thereon, a jack-top fixed to the bar and extending rearwardly over the base, a driver-assembly movable in the space between the base and jack-top, and a sheet-metal shield enclosing the space.

60 21. In a shoe-nailing machine, a base provided with a flat front in which is a transverse depression, a bar engaging the flat portion of the base and having a projection entering the depression, said bar being divided 65 at its upper extremity, and a jack-top secured

to the divided portion of the bar and extending rearwardly over the base.

22. In a shoe-nailing machine, a base provided with a flat front in which is a transverse depression, a bar engaging the flat portion of the base and having a projection entering the depression, said bar being divided at its upper extremity, a jack-top secured to the divided portion of the bar and extending rearwardly over the base, a driver-assembly 70 guided in the base and reciprocating through the space between said base and the jack-top at the rear of the bar, and a shield surrounding the space and secured to opposite sides of the bar. 75

23. In a machine for operating upon the heel-portions of shoes, a support for a shoe and heel, a pressure-abutment including a heel-breast-engaging member, said abutment and engaging member being initially separated from the heel upon the support, and means for moving the support and abutment relatively to bring said abutment and the heel upon the supported shoe into contact, continued relative movement establishing engagement between the breast member and heel. 80

24. In a machine for operating upon the heel-portions of shoes, a support for a shoe and heel, a pressure-abutment including a 85 member for engagement with the rear of a heel and a heel-breast-engaging member, means for moving the support and abutment relatively to bring one of the engaging members and the corresponding portion of the heel on the supported shoe into contact, and connections between the members constructed and arranged to establish engagement between the other engaging member and the heel upon continued relative movement. 90

25. In a machine for operating upon the heel-portions of shoes, a support for a shoe and heel, a pressure-abutment including a member for engagement with the rear of a heel and a heel-breast-engaging member, 110 means for moving the abutment to bring the rear engaging member into contact with the heel of a supported shoe, and connections between the members constructed and arranged to move the breast-engaging member upon 115 continued movement of the abutment.

26. In a machine for operating upon heels, a frame, a jack secured thereon and arranged to support a heel, a reciprocating pressure-abutment guided upon the frame and movable into contact with a heel on the jack, and a heel-breast-pressure member carried by the abutment and movable thereon into engagement with the heel after contact between the heel and the abutment. 120

27. In a machine for operating upon heels, a frame, a jack secured thereon, a reciprocating pressure-abutment guided upon the frame, a heel-breast-pressure member carried by the abutment, and means acting during the 130

movement of the abutment for carrying the member into contact with the breast of a heel upon a jacked shoe.

28. In a machine for operating upon the heel-portions of shoes, a jack, a pressure-head co-operating therewith, a heel-contact member yieldably mounted upon the head, a second heel-contact member pivoted upon the head, and connections between the members arranged to turn the pivoted member during the yield of the companion member.

29. In a machine for operating upon the heel-portions of shoes, a jack, a pressure-head co-operating therewith, a heel-contact member yieldably mounted upon the head, a second heel-contact member pivoted upon the head, a rack carried by the yieldable member, and a pinion secured to the companion member at its pivot and meshing with the rack.

30. In a heel-attaching machine, a jack, driving mechanism arranged to insert through the heel-seat of a jacked shoe into a heel held thereon, a nail inclined from the rear of the heel toward the breast, and a pressure-head having a member contacting with the breast of the heel.

31. In a machine for attaching heels of the Louis type, a jack, driving mechanism arranged to insert through the heel-seat of a jacked shoe into a heel held thereon a nail inclined from the rear of the heel toward the breast, and a pressure-head having a member contacting with the curved portion of the breast of the heel adjacent to the shoe-bottom.

32. In a machine for operating upon heels, a work-support, a pressure-head co-operating therewith, heel-contact members movable upon the head, connections arranged to move one member from another, and means arranged to positively prevent reverse movement of one of the members upon the head.

33. In a machine for operating upon heels, a work-support, a pressure-head co-operating therewith, heel-contact members movable upon the head, connections arranged to move one member from another toward a heel upon the support, and a locking member constantly effective during movement of the member toward the heel to prevent reverse movement.

34. In a machine for operating upon heels, a work-support, a pressure-head co-operating therewith, heel-contact members movable upon the head, connections arranged to move one member from another toward a heel upon the support, a locking member effective to prevent reverse movement of the heel-contact member thus moved, and means for releasing the locking member.

35. In a machine for operating upon heels, a work-support, a pressure-head co-operating therewith, heel-contact members movable upon the head, connections arranged to move one member from another toward a heel upon the support, a locking member effective to

prevent reverse movement of the heel-contact member thus moved, means for releasing the locking member, and means arranged to vary the time of action of the releasing means.

36. In a machine for operating upon heels, a work-support, a pressure-head movable toward and from the support, heel-contact members movable upon the head, connections arranged to move one member from another toward a heel upon the support, a locking member effective to prevent reverse movement of the heel-contact member thus moved, and means made effective in the movement of the head for releasing the locking member.

37. In a machine for operating upon heels, a work-support, a pressure-head co-operating therewith, a member movable upon the head into contact with the breast of a heel upon the support, and a lock arranged to prevent reverse movement of the breast-contact member.

38. In a machine for operating upon heels, a work-support, a pressure-head co-operating therewith, a member movable upon the head into contact with a heel upon the support, and a ratchet and detent co-operating to prevent reverse movement of the contact member.

39. In a machine for operating upon heels, a work-support, a pressure-head co-operating therewith, a member movable upon the head into contact with a heel upon the support, a ratchet and detent co-operating to prevent reverse movement of the contact member, and means for separating the ratchet and detent to free the contact member.

40. In a machine for operating upon heels, a work-support, a pressure-head co-operating therewith, a lever fulcrumed upon the head and arranged for contact with a supported heel, a ratchet movable with the lever, and a detent movable upon the head into engagement with the ratchet.

41. In a machine for operating upon heels, a work-support, a pressure-head movable toward and from the support, a lever fulcrumed upon the head and arranged for contact with a supported heel, a ratchet movable with the lever, a detent movable upon the head into engagement with the ratchet, and a relatively fixed member which the detent engages in the movement of the head.

42. In a machine for operating upon heels, a work-support, a pressure-head movable toward and from the support, a lever fulcrumed upon the head and arranged for contact with a supported heel, a ratchet movable with the lever, a detent movable upon the head into engagement with the ratchet, a relatively fixed member which the detent engages in the movement of the head, and means arranged to vary the position of the engaged member.

43. In a machine for operating upon the heel-portions of shoes, a work-support, a

pressure-head, and a lever fulcrumed upon the head for contact with a supported heel, the contact-arm of the lever being in relatively adjustable sections.

- 5 44. In a machine for operating upon the heel-portions of shoes, a work-support, a pressure-head, a lever fulcrumed upon the head for contact with a supported heel, the contact-arm of the lever being in relatively adjustable sections, and an adjusting member rotatable upon one lever-section and engaging the other.

- 10 45. In a machine for operating upon the heel-portions of shoes, a work-support, a pressure-head, a heel-breast contact member movable upon the head and having relatively adjustable sections, a worm rotatable upon one section, and a worm-wheel carried by the other section and meshing with the worm.

- 15 46. In a heel-attaching machine, a jack, a contact device having members arranged to contact with opposite sides of a heel to be attached to a jacked shoe, and means arranged to vary independently the angular position of the contact members upon the device.

- 20 47. In a heel-attaching machine, a jack, a contact device having levers extending at opposite sides of a heel to be attached to a jacked shoe, and a heel-contact member adjustably mounted upon each lever.

- 25 48. In a heel-attaching machine, a jack, a contact device having levers extending at opposite sides of a heel to be attached to a jacked shoe, a heel-contact member adjustably mounted upon each lever, and means for securing the members in their adjusted positions.

- 30 49. In a heel-attaching machine, a jack arranged to support a shoe and a heel to be attached, a pressure-head co-operating with the jack, means for moving the head and jack relatively, a heel-contact member movable upon the head, and means arranged to adjust the position of the member transversely of the length of a jacked shoe.

- 35 50. In a heel-attaching machine, a jack arranged to support a shoe and a heel to be attached, a pressure-head mounted to reciprocate toward and from the jack, a heel-contact member movable upon the head, and means arranged to adjust the position of the member longitudinally and transversely of a jacked shoe.

- 40 51. In a heel-attaching machine, a jack arranged to support a shoe and a heel to be attached, a pressure-head mounted to reciprocate toward and from the jack, a member movable upon the head and arranged for contact with the rear of a heel associated with a jacked shoe, and means arranged to adjust the position of the member transversely of the heel.

- 45 52. In a heel-attaching machine, a jack arranged to support a shoe and a heel to be

attached, a pressure-head mounted to reciprocate toward and from the jack, a slide movable vertically in the head and having horizontal ways at its lower extremity, a slide movable in the ways, means made effective in the travel of the head for moving the slide, and a heel-contact member carried by the horizontal slide.

50 53. In a machine for operating upon heel-portions of shoes, a work-support, a pressure device movable toward and from the work-support, a contact member movable upon the pressure device, and means along which the contact member is moved by the pressure device and which is constructed and arranged to effect its movement upon said device.

55 54. In a machine for operating upon heel-portions of shoes, a work-support, a pressure device movable toward and from the work-support, a contact member movable upon the pressure device, an actuating member along which the pressure device travels arranged to effect movement of the contact member, and means movable with the pressure device and arranged to move the actuating member.

60 55. In a machine for operating upon heel-portions of shoes, a work-support, a pressure device movable toward and from the work-support, a plurality of heel-contact members movable upon the pressure device, and means acting in the movement of the pressure device for moving the plural members upon said device.

65 56. In a heel-attaching machine, a frame, a pressure-head reciprocating upon the frame, a slide movable upon the head, a heel-contact member mounted upon the slide, and a member carried by the frame and along which the pressure-head travels to move the slide upon said head.

70 57. In a heel-attaching machine, a frame, a pressure-head reciprocating upon the frame, a slide movable upon the head, a heel-contact member mounted upon the slide, and a member carried by the frame and made effective by the travel of the head to move the slide.

75 58. In a heel-attaching machine, a frame, a pressure-head reciprocating upon the frame, a slide movable upon the head, a heel-contact member mounted upon the slide, and a lever fulcrumed upon the frame and contacting with the slide, the pressure head acting upon the slide to effect its movement.

80 59. In a heel-attaching machine, a frame, a pressure-head reciprocating upon the frame, a slide movable upon the head, a heel-contact member mounted upon the slide, a lever fulcrumed upon the frame, and a cam movable by the head to force the lever against the slide.

85 60. In a heel-attaching machine, a frame, a pressure-head reciprocating upon the

frame, a slide movable upon the head, a heel-contact member mounted upon the slide, a member carried by the frame and arranged to move the slide forward, and a spring connected to the frame and slide and arranged to move said slide to the rear.

61. In a heel-attaching machine, a support for a shoe and heel, heel-pressure means having movable members mounted independently of one another and arranged for contact with the rear, breast and opposite sides of a supported heel, and means common to all these contact members and acting upon them to cause their engagement with the heel.

62. In a heel-attaching machine, a support for a shoe and heel, heel-pressure means having movable members mounted independently of one another and arranged for contact with the rear, breast and opposite sides of a supported heel, and actuating connections between the rear and side members.

63. In a heel-attaching machine, a support for a shoe and a heel, a pressure-head co-operating with the support, a rear heel-contact member yieldable upon the head, side heel-contact members, and connections for the rear member to the side members to actuate the latter.

64. In a machine for operating upon the heel-portions of shoes, a support for a shoe and heel, a pressure-abutment having two heel-engaging members, one of said members being arranged for engagement with the heel-breast, means for moving the support and abutment relatively to bring one of the engaging members and the heel upon the support into contact, and connections between the engaging members for thereafter moving the other engaging member into engagement with the heel.

65. In a machine for operating upon the heel-portions of shoes, a support for a shoe and heel, a pressure-abutment including a heel-breast-engaging member, means for moving the support and abutment relatively to bring said abutment and the heel upon the supported shoe into contact, and means acting after contact between the abutment and heel has been established to produce engagement between the breast member and heel.

66. In a machine for operating upon the heel-portions of shoes, a support for a shoe and heel, a pressure-abutment having two heel-engaging members, one of said members being arranged for engagement with the heel-breast, means for moving the support and abutment relatively to bring one of the engaging members and the heel upon the support into contact, means for thereafter moving the other engaging member into engagement with the heel, and means arranged to positively prevent reverse movement of said other engaging member.

67. In a machine for operating upon the heel-portions of shoes, a jack, a pressure-head

co-operating therewith, a heel-contact member yieldably mounted upon the head, a second heel-contact member movable upon the head and having a pivotal mounting, and means movable with the yieldable contact member and arranged to turn the pivoted contact member.

68. In a machine for operating upon the heel-portions of shoes, a jack, a pressure-head co-operating therewith, a heel-contact member yieldably mounted upon the head, a second heel-contact member movable upon the head and having a pivotal mounting, means movable with the yieldable contact member and arranged to turn the pivoted contact member, and means for locking the pivoted member against reverse movement.

In testimony whereof I have signed my name to this specification.

CERTIFICATE OF CORRECTION.

Patent No. 1,895,896.

January 31, 1933.

ELMER R. POPE.

It is hereby certified that error appears in the printed specification of the above numbered patent requiring correction as follows: Page 4, line 78, for "which is held, for regular adjustment, a" read "and both the rear and breast-contact"; and that the said Letters Patent should be read with this correction therein that the same may conform to the record of the case in the Patent Office.

Signed and sealed this 22nd day of August, A. D. 1933.

M. J. Moore.

(Seal)

Acting Commissioner of Patents.
